ARTHUR CONSTANTIN KREBS, OF PARIS, FRANCE, ASSIGNOR TO SOCIÉTÉ ANONYME DES ANCIENS ÉTABLISSEMENTS PANHARD ET LEVASSOR, OF PARIS, FRANCE.

CONE-CLUTCH.

SPECIFICATION forming part of Letters Patent No. 734,893, dated July 28, 1903.

Application filed January 30, 1902. Serial No. 91,870. (No model.)

To all whom it may concern:

Be it known that I, ARTHUR CONSTANTIN KREBS, a citizen of the Republic of France, residing in Paris, France, have invented certain new and useful Improvements in Cone-Clutches, of which the following is a specification.

This arrangement has for its object to produce the driving of one shaft by another by means of a cone-clutch without there being exterior action of these shafts in the axial direction.

In the accompanying drawings, Figures 1 and 2 are diagrammatic sections of two different embodiments of the invention. Fig. 3 is a longitudinal section of the embodiment shown diagrammatically in Fig. 1. Fig. 4 is a section on the line 4-4 of Fig. 3.

The general arrangement shown in Figs. 1 and 2 consists in placing the two cones *a* and *b* so that the one, *a*, is in connection with the shaft that is to be driven, the other, *b*, free on this shaft, but connected to the driving-shaft by studs *c*, which allow *b* to move longitudinally. The two cones *a* and *b* are acted on by a spring *d*, the equal and opposite actions of which are finally supported, when the cones are engaged by the driven shaft, and consequently do not tend to move it lengthwise. Unclutching is effected by acting on the cone *b* in the direction to compress the spring. The driven shaft cannot move under the action of the spring during the unclutching movement, being held by the stop *x*.

The motor-shaft *m* has on it the fly-wheel *v*, having two projecting driving-studs *c*, which engage in holes bushed with steel *e* in the periphery of the driving clutching-cone *b*, which has a covering *f* of leather. The cone *b* is fitted on a sleeve *g*, which is free on the driven shaft *h*. The sleeve *g* has collars and grooves which engage in an external sleeve *k*, made in two pieces, held together by a ring *l*. A helical spring *d* bears at one end against the external sleeve, and at the other end against the stop *n*, which is screwed on the shaft *h*. By the action of the spring *d* the external sleeve pushes the cone *b* against the driven cone *a* without moving the latter on its shaft *h*, since this shaft is subject to

the equal and opposite action of the other end of the spring *d* on the stop *n*.

In order to unclutch, a fork-lever *p*, pivoted at *q* to any suitable stationary support, (not shown), engages a groove *o* in the external sleeve *k*. By pressing the arm *r* in the direction of the arrow the cone *b* is moved back. Its sleeve *g* is quite free and can turn without putting any stress on the collar of the external sleeve *k*. Consequently it cannot transmit any motion to the shaft *h* though the cone *b* continues to revolve with the fly-wheel of the motor. Thus the unclutching is complete.

An important feature of my improved clutch and which adapts it especially for clutching a driving-shaft and a driven shaft which are in line with each other is that the studs *c*, by reason of the slight play which they necessarily have in the steel bushings *e*, give a certain flexibility to the connection, so as to permit a slight deviation of either of the shafts out of its true line, as if they were connected by a laterally-yielding connection.

Having thus described the nature of this invention and the best means I know of for carrying the same into practical effect, I claim—

1. In a friction-clutch, the combination of a shaft having a shoulder, sleeves *g* and *k* on said shaft and connected to each other and adapted to rotate relatively to each other and to slide together on said shaft, a friction member *b* attached to the sleeve *g*, a spring bearing at opposite ends against said shoulder and said sleeve *k* respectively, whereby friction between the spring and the friction member *b* is avoided, and a reciprocal friction member adapted for engagement with said member *b*.

2. A friction-clutch comprising in combination a driving-shaft and a driven shaft which are in line with each other, a driving friction member connected for rotation with said driving-shaft and loosely mounted on said driven shaft so as to be rotatable and slidable thereon, a driven friction member connected to said driven shaft, a shoulder on said driven shaft, a spring on said driven shaft bearing at one end against said shoulder and at the other end against said driving friction member.

member to move the same into engagement with said driven friction member to clutch said shafts to each other, and means for moving the same out of engagement with said 5 driven friction member.

3. A friction-clutch comprising in combination a driving-shaft and a driven shaft which are in line with each other, a friction member connected for rotation with one of 10 said shafts and loosely mounted on the other of said shafts so as to be rotatable and slideable thereon, a reciprocal friction member connected to the same shaft upon which said first friction member is mounted, a spring 15 acting to move said first-mentioned friction member longitudinally, and a sleeve interposed between the spring and the friction member and rotatively connected to the friction member.

20 4. A friction-clutch for clutching a driving-shaft and a driven shaft which are in line with each other, comprising in combination a wheel on said driving-shaft and having

studs, a driving friction member having holes in which said studs engage to connect said 25 member for rotation with said wheel and to permit longitudinal movement relatively thereto, said driving friction member being loosely mounted on the driven shaft so as to be rotatable and slideable thereon, a driven 30 friction member connected to the driven shaft, a shoulder on said driven shaft, a spring on said driven shaft bearing at one end against said shoulder and at the other end against said driving friction member to move the 35 same into engagement with said driven friction member, and means for moving the same out of engagement with said driven friction member.

In witness whereof I have hereunto signed 40 my name in the presence of two subscribing witnesses.

ARTHUR CONSTANTIN KREBS.
